NICOTINIUM ALKYL SULFATES

Joseph B. Niederl, Brooklyn, N. Y., and Martin E. McGreal, Sommersworth, N. H., assignors to J. B. Niederl & Associates, Inc., New York, N. Y., a corporation of New York

No Drawing. Application August 11, 1948,
Serial No. 43,778

3 Claims. (Cl. 260—291)

1

This invention generally is a continuation-in-part of patent application Serial No. 787,468, filed November 21, 1947, now abandoned, and entitled, "N,N-dialkyl morpholinium alkyl sulfates," and of patent application Serial No. 41,728, filed July 30, 1948, entitled, "Unsymmetrical quaternary ammonium alkyl sulfates."

More specifically the present invention relates to nicotinium alkyl sulfates of the general formula:

in which R is an alkyl radical from one to eighteen carbon atoms, Y an alkyl or cyclo-alkyl radical from three to eighteen carbon atoms and x either one or two. Nicotinium alkyl sulfates of the above formula, in which, however, R and Y are identical and alkyl radicals of only one or two carbon atoms (nicotinium metho- or etho sulfates) have been known before. They are prepared by the action of equimolar or double molar quantities of di-methyl or di-ethyl sulfate upon nicotine.

The method of preparation involved in this invention involves the reaction of nicotine (d- or l, or dl-) with equimolar, or double molar quantities of a symmetrical or an unsymmetrical di-alkyl sulfate, giving rise to four distinct possibilities as illustrated below:

- (a) $C_{10}H_{14}N_2 + Y_2SO_4 \rightarrow C_{10}H_{14}N_2Y^+SO_4Y^-$
- (b) $C_{10}H_{14}N_2 + 2Y_2SO_4 \rightarrow C_{10}H_{14}N_2Y^+ (SO_4Y)_2^-$
- (c) $C_{10}H_{14}N_2 + RSO_4Y \rightarrow C_{10}H_{14}N_2R^+ + SO_4Y^-$
- (d) $C_{10}H_{14}N_2 + 2RSO_4Y \rightarrow C_{10}H_{14}N_2R_2^+ (SO_4Y)_2^-$

[Y>R]

Processes (a) and (b) will give rise to nicotinium alkyl sulfates in which the carbon content of the cation is larger than that of the anion. On the other hand, processes (c) and (d) will yield nicotinium alkyl sulfates in which the carbon content of the anion is equal ("Equionics") or larger than that of the cation. The latter two types of nicotinium compounds being entirely new.

In the present invention, in processes (a) and (b) the following symmetrical di-alkyl sulfates have been used: di-n-propyl-, n-butyl-, n-amyl-, n-hexyl-, n-heptyl-, n-octyl-, n-decyl-, lauryl-, myristyl-, cetyl- and octadecyl sulfates. Also unsaturated alkyl sulfates as well as cyclo-alkyl sulfates can be employed in the above reactions.

In carrying out processes (c) and (d) usually methyl-alkyl sulfates were employed, in which the alkyl radicals were: n-hexyl-, cyclohexyl-, n-octyl-, n-decyl-, (4-t-amyl) cyclohexyl-, lau-

2

ryl-, myristyl-, cetyl and octadecyl. Instead of the methyl sulfates cited above, also the corresponding ethyl sulfates may be used, which, however, necessitates a longer reaction period.

With the many reaction possibilities as outlined above, it is now possible to prepare nicotinium compounds with predetermined properties, such properties manifesting themselves in certain outstanding physical, chemical and physiological characteristics. These characteristics involve unusual solubility behaviour, capillary activity and detergency. Furthermore also intramolecular synchronization of bactericidal and fungicidal action with insecticidal qualities has been realized. Generally, the postulations given in the aforementioned concomitant patent applications apply without reservation also to this particular case, which is, however, much more important as it involves compounds possessing not only one but two anionoidic, as well as cationoidic centers, in addition to the a priori inherent physiological behaviour of the alkaloid used in this invention.

Thus many of the compounds described herein are detergents and emulsifying agents in both, aqueous and non-aqueous media. Many are also effective germicides, fungicides and insecticides.

Example 1.—Nicotine with symmetrical di-alkyl sulfates

One tenth mol of redistilled, commercial nicotine and one tenth mol of di-n-decyl sulfate (B. P. 145–150°/8. mm.) are placed into a 100 cc. round bottomed Pyrex-flask and the reactants well mixed. The flask is well stoppered and immersed into an oil bath. The reaction mixture is then heated for twelve hours at 110–115° C. After this time the reaction mixture is allowed to cool. Fifty cc. of ether is then added to the cold reaction mixture and the mass well stirred. Finally, after attaching a water reflux condenser to the flask, the mixture is gently heated in water bath at about 35–40° C. for about 10 minutes. During this heating period the content of the flask is either well stirred or shaken repeatedly. Then the reaction mixture is allowed to cool and the ether layer decanted off. The procedure of ether extraction is repeated twice to remove completely any unreacted starting materials. The ether-insoluble residue is recrystallized from hot ethyl alcohol. The N-decyl-nicotinium decyl sulfate thus produced melts at 78–79° C. It is insoluble in ether, but soluble in hot alcohol, acetone or ethyl acetate. It forms foaming solutions with water.

Using the above procedure the following N-alkyl nicotinium alkyl sulfates were prepared using redistilled commercial nicotine and equimolar quantities of the symmetrical di-alkyl sulfates indicated below:

Compounds: Mono Sulfates	Di-alkyl Sulfates (1 mol)
N-n-Propyl-Nicotinium n-propyl	Di-n-propyl.
N-n-Butyl-Nicotinium n-butyl	Di-n-butyl.
N-n-Amyl-Nicotinium n-amyl	Di-n-amyl.
N-n-Hexyl-Nicotinium n-hexyl	Di-n-hexyl.
N-n-Octyl-Nicotinium n-octyl	Di-n-octyl.
N-Lauryl-Nicotinium lauryl (M. P. 82-84° C.)	Di-lauryl.
N-Myristyl-Nicotinium myristyl (M. P. 74-77° C.)	Di-myristyl.
N-Octyl-Nicotinium cetyl (M. P. 72-73° C.)	Di-cetyl.
N-Octadecyl-Nicotinium octadecyl (M. P. 76-80° C.)	Di-octadecyl.

Employing the same experimental procedure, but using double molar quantities of the symmetrical di-alkyl sulfate and redistilled commercial nicotine, the following N,N-di-alkyl-nicotinium di-alkyl sulfates were prepared:

Compounds: Di-Sulfates	Di-alkyl Sulfates (2 mols)
N,N-Di-n-propyl-Nicotinium di-n-propyl	di-n-propyl sulfate.
N,N-Di-n-butyl-Nicotinium di-n-butyl	di-n-butyl sulfate.
N,N-Di-n-amyl-Nicotinium di-n-amyl	di-n-amyl sulfate.
N,N-Di-n-hexyl-Nicotinium di-n-hexyl	di-n-hexyl.
N,N-Di-n-octyl-Nicotinium di-n-octyl	di-n-octyl.
N,N-Di-n-decyl-Nicotinium di-n-decyl (M. P. 95-96° C.)	di-n-decyl.
N,N-Di-lauryl-Nicotinium di-lauryl (M. P. 97-98° C.)	di-lauryl.
N,N-Di-myristyl-Nicotinium di-myristyl (M. P. 98-100° C.)	di-myristyl.
N,N-Di-cetyl-Nicotinium di-cetyl (M. P. 100-101° C.)	di-cetyl.
N,N-Di-octadecyl-Nicotinium di-octadecyl (M. P. 102-104° C.)	di-octadecyl.

Example 2.—Nicotine with unsymmetrical di-alkyl sulfates

One tenth mol of redistilled commercial nicotine and one fifth mol of methyl-cetyl sulfate (M. P. 72-73° C.) are introduced into a 100 cc. round bottom Pyrex flask, the two reactants are well mixed, and the flask well stoppered. The flask is then heated on a steam bath, at a temperature of about 90° C. for about forty hours. After this time the contents of the flask are allowed to cool. Afterwards the solid reaction mixture is broken up and is then triturated with 50 cc. of ether, first in the cold and later with warming on a steam bath. After cooling, the ether layer is decanted off. This procedure is repeated twice. The final product is crystallized from boiling ethyl alcohol. The compound, the 45 Number 55 compound, the N,N-dimethyl-nicotinium di-cetyl di sulfate melts at 163-165° C. (uncorr.). It is insoluble in ether, but soluble in hot ethyl acetate, ethyl alcohol and acetone.

Following the procedure given above, the using 60 equimolar quantities of nicotine and the unsymmetrical methyl-alkyl sulfates enumerated below, the following N-methyl-nicotinium alkyl sulfates were obtained:

Compounds: Mono Sulfates	Methyl-alkyl Sulfates (1 mol)
N-Methyl-Nicotinium n-hexyl	-n-hexyl.
N-Methyl-Nicotinium n-octyl	-n-octyl.
N-Methyl-Nicotinium n-decyl	-n-decyl.
N-Methyl-Nicotinium lauryl (M. P. 122-127° C.)	-lauryl.
N-Methyl-Nicotinium myristyl (M. P. 123-126° C.)	-myristyl.
N-Methyl-Nicotinium cetyl (M. P. 126-127° C.)	-cetyl.
N-Methyl-Nicotinium octadecyl (M. P. 133-135° C.)	-octadecyl.

Compounds: Di-Sulfates	Methyl-alkyl Sulfates (2 mols)
N,N-Dimethyl-Nicotinium di-n-hexyl	-n-hexyl.
N,N-Dimethyl-Nicotinium di-n-octyl	-n-octyl.
N,N-Dimethyl-Nicotinium di-n-decyl	-n-decyl.
N,N-Dimethyl-Nicotinium di-lauryl (M. P. 157-160° C.)	-lauryl.
N,N-Dimethyl-Nicotinium di-myristyl (M. P. 158-162° C.)	-myristyl.
N,N-Dimethyl-Nicotinium di-octadecyl (M. P. 165-170° C.)	-octadecyl.

Compounds: Equionics	Di-alkyl Sulfates
N,N-Dimethyl-Nicotinium di-n-hexyl di sulfate.	methyl-n-hexyl (2 mols).
N,N-Dimethyl-Nicotinium di-cyclohexyl di sulfate.	methyl-cyclohexyl (2 mols).
N-Methyl-Nicotinium (4-t-amyl) cyclohexyl sulfate.	methyl-(4-t-amyl) cyclohexyl (1 mol).

What we claim is:

1. Nicotinium alkyl sulfates of the general formula:

in which R is an alkyl radical from one to eighteen and Y an alkyl radical from six to eighteen carbon atoms and x one and two.

2. Nicotinium alkyl sulfates of the general formula:

in which R is an alkyl radical from one to eighteen and Y an alkyl radical from six to eighteen carbon atoms.

3. Nicotinium alkyl sulfates of the general formula:

in which R is an alkyl radical from one to eighteen and Y an alkyl radical from six to eighteen carbon atoms.
